UNITED STATES PATENT OFFICE.

AMBROSE KINNICUTT, OF ALBANY, NEW YORK.

DESIGN FOR A PUZZLE-BOARD.

SPECIFICATION forming part of Design No. 33,123, dated August 28, 1900.

Application filed July 23, 1900. Serial No. 24,613. Term of patent 7 years.

To all whom it may concern:

Be it known that I, AMBROSE KINNICUTT, a citizen of the United States, residing at the city and county of Albany, State of New York, have invented and produced a new and original Design for a Puzzle-Board, of which the following is a specification, reference being had to the accompanying drawing, forming a part thereof, in which the figure is a perspective view.

As shown in the drawing, the leading or material feature of my design consists in a rectangular box A, provided with a series of curved projecting strips B B, arranged adjacent to but separated from each side of the box, respectively, placed with the concave side of the strip toward the side of the box,

with two curved strips C C, arranged about midway between the sides of the box, separated slightly from each other, each presenting its concave side to the other and arranged so that one of the strips shall extend beyond the other.

Having described my invention, what I claim as new, and desire to secure by Letters Patent, is—

The design for a puzzle-board as herein shown and described.

Signed by me at Albany, New York, this 16th day of July, 1900.

AMBROSE KINNICUTT.
